ARRANGEMENT OF NONINDUCTIVE TERMINALS FOR VARIABLE CONDENSERS

Adriano Cavalieri Ducati, Bologna, Italy

Application December 20, 1937, Serial No. 180,854
In Italy December 19, 1936

2 Claims. (Cl. 175—41.5)

(Granted under the provisions of sec. 14, act of
March 2, 1927; 357 O. G. 5)

The present invention relates to precision electrostatic condensers and more particularly relates to a system of terminals for variable electrostatic condensers minimizing the inductance or inductive reaction for the electrical connection to the condensers.

The greatest value of a precision variable condenser such as is employed in laboratories or in electrical measurements or comparisons is constancy of its capacity over a great range of applied frequency. The capacity of a precision variable condenser depends upon its inherent capacity which can be determined to a fraction of a micro-microfarad. However, the effective capacitance of the condenser depends also to some degree upon the frequency of the applied signal. The inherent inductance in the condensers of the prior art caused a variation in the effective condenser capacitance which changed with the frequency applied thereto, the higher the frequency range, the greater the variation in the effective capacitance of the condenser and therefore its determinable accuracy.

The inherent inductance of a precision variable condenser is very important, particularly at the higher frequency such as in radio frequency or ultra-high frequency use, even though its value may be a one-hundredth or smaller part of a microhenry. I have found that the terminal connections to the variable condenser produce the greater portion of the inductance of the condenser, and it is among the objects of my present invention to minimize the inductive reaction of the contacts to the variable condenser.

In accordance with my present invention, I contemplate arranging the terminal connections to the plates thereof in a manner to nullify or greatly minimize the inductance thereof as compared to the prior art condensers. In one form of the invention, I provide the terminals to the stationary and rotary plates of the condenser concentrically arranged whereby any self-inductive reaction of any one terminal is cancelled or nullified by that of the other one. In a modification of my invention I provide two closely adjacent terminal posts adapted to greatly minimize the inductive reaction of the connection to the condenser plates. By thus minimizing the inductance of the variable condenser, the capacity thereof remains more constant over a much greater frequency range than the condensers of the prior art.

It is accordingly an object of my present invention to provide a novel system of terminal contacts for a variable condenser.

It is another object of my present invention to provide a novel arrangement for connection to the stator and rotor plates of a precision electrostatic condenser.

60 It is still another object of my present inven-

tion to materially minimize the inherent inductance of variable electrostatic condensers.

These and further objects of my present invention will become apparent in the following description taken in connection with the drawing in which:

Figure 1 is an end view of a preferred construction of a variable condenser in accordance with my present invention with the turning knob omitted and represents the view taken along 1—1 in Figure 2.

Figure 2 is a plan view of the condenser shown in Figure 1.

Figure 3 is a perspective view partly in section of a modified form of my present invention.

Figure 4 is a schematic view of still a further form of my invention.

Figure 5 is a diagrammatic illustration of the principle embodied in my invention.

In Figure 1 I have illustrated a semi-circular type condenser construction comprising the fixed or stator portion 10 and rotatable or rotator portion 11. The stator portion 10 is affixed or mechanically secured to the terminal or contact rod 12, together with the stud 13 as shown in Figures 1 and 2. The rotor section 11 is centrally secured to the rod 14 together with the stud 15. A knob 16 may be affixed at the projecting end of the terminal post 14 as shown in Figure 2. The rods 12 and 14 may be of small diameter and of solid metallic conducting material such as aluminum, copper or the like, or may well be hollow or tubular in accordance with principles of design for minimizing condenser losses well known in the art.

In accordance with the principle of my present invention, the disposition of the rotor and stator plates 10 and 11 and the terminal posts 12 and 14 respectively are arranged whereby the terminals 12 and 14 may be as physically close together as possible, more so than any of the condensers of the prior art. As will be hereinafter pointed out, such close disposition of the terminal rods 12 and 14 parallelly arranged as seen in Figure 2 makes for a constancy of capacity for the unit with a minimum of inherent inductance.

In order to provide for a 180° rotation for the rotor 11 in the preferred physical arrangement as described and without mechanically interfering with the terminal post 12 of the stator 10, the cut-away section 16 in the rotor plate 11 obviates the mechanical interference between the rotor plates 11 and the post 12 as will now be evident. I further provide a cut-away portion 17 in the stator plate, to permit closer positioning between the posts 12 and 14 and avoid the necessary projecting portion of the stud 15 and post 14 as will also now be evident. Accordingly, it is to be understood that the design of the condenser plates 10 and 11 with the provided cut-

away sections 16 and 17 are for permitting as physically close positioning of the terminal posts 12 and 14 as practicable and furthermore permit a full 180° rotation of the rotor section 11 of the condenser. It is to be further understood that the illustrations I have made are with a single plate rotor and single plate stator for simplicity of illustration and that a plurality of such plates may be used with the modifications I have described as will be evident to those skilled in the art. Terminal leads 19 are connected to the extremity of the parallel terminal rods 12 and 14. The non-inductive arrangement of the flexible leads 18 may be arranged in any manner known in the art, the present invention being particularly concerned with the minimizing of inductive reaction of the electrical condensers per se.

A modified form in applying my invention to variable condenser construction is illustrated in Figure 3 wherein a fixed or stator plate section 20 is arranged opposite the rotor plate 21 adapted to be rotated by the central connection rod 24 to which it is secured. A knob 28 is preferably affixed to a projection of the central rod 24 as shown in the figure. The knob 28 is naturally of insulation material to permit handling by the operator.

The stator 20 is secured to a metallic tube 22 which is concentric about and co-extensive with the central rotor connection rod 24. It is to be understood that the tube 22 preferably completely surrounds the rod 24 and is broken away in the illustration. Insulation bushings 25 electrically separate and maintain the connection posts 22 and 24 in proper mechanical and electrical relation. The wire leads 29 connect to the terminal rods 22 and 24 as shown to connect the condenser to the necessary electrical circuits.

40 The application of my invention is not limited to the particular shape or arrangement of the condenser plates. In Figure 4 I illustrate a condenser having square-shaped plates 30 and 31. The rotor 31 has a cut-away section 32 adapted 45 to prevent mechanical interference between the rotor 31 and the terminal rod 33 of the stator plate 30. The terminal rod 34 of the rotor plate 31 is adapted to be secured to a knob or other element for rotation. It is to be understood 50 that the mechanical disposition of the terminal rods 33 and 34 are similar to the hereinabove described arrangement in connection with Figures 1 and 2 of rods 12 and 14 to cause minimum inductive action by the terminal rods.

55 The principle of minimizing the inherent inductance of the terminal connections for the variable condensers of my present invention is predicated upon the phenomena of minimizing inductance by arranging two conductors in parallel and in close juxtaposition and in causing similar currents to flow therein in opposite directions. The schematic diagram forming Figure 5 is included to illustrate this principle. The two conductors 40 and 41 are arranged in parallel. These conductors may be the opposite plates of a condenser or may well represent the parallel terminal rods 12 and 14 of Figure 2; or 22 and 24 of Figure 3. The horizontal arrows represent the direction of the current i flowing 60 therein. The current i in the conductors 40 and 41 are necessarily of substantially equal value due to the series relation. The transverse arrows between the plates 40 and 41 represent the capacitive relation or reaction C between these

plates or conductors which, being a geometric entity is substantially constant for wide frequency ranges.

I have placed corresponding arrows upon the Figures 2 and 3 to represent the direction of flow 5 of the currents in the parallel terminal contacts and condenser plates to indicate how the principle of minimizing the inductive reaction of them is effected by my invention.

It is to be understood that the terminal rods 10 of the condensers are arranged to be placed as close together as possible to minimize as much as possible the inductive reaction thereof as will now be understood by those skilled in the art. The cut-away portions illustrated in some of 15 the modifications permit close positioning of the terminal rods. In the modification of Figure 3, the concentric relation of the terminal rods affords the theoretical minimum of inductance therefor. My invention is applicable for all types 20 of variable condensers irrespective of their shape or use and is designed to minimize the inherent inductance therein to provide a substantially constant effective capacitance of the condenser over wide frequency ranges and particularly for 25 high radio frequency precision measurements.

Having described particular embodiments of my invention, modifications which fall within the broader spirit and scope of my invention may be evident to those skilled in the art and accordingly, I do not intend to be limited except as set forth in the following claims.

I claim:

1. A high frequency precision variable condenser comprising a stator section of substantially semi-circular shape, a rotor section of substantially semi-circular shape, a terminal rod secured solely to one region of said rotor adapted to rotate said rotor, a second terminal rod secured solely to one region of said stator, said rods being parallel and arranged mechanically close for minimizing the inductive reaction thereof, said rotor section having a cut-away portion to permit the close positioning of said rods and full effective one-hundred and eighty degree rotation of said rotor, whereby the flow of high frequency current in the condenser through said rods, rotor and stator substantially cancel inductive reaction therein to provide a stable effective capacitance for the condenser when operated at high frequencies.

2. A high frequency precision variable condenser comprising a stator section of substantially semi-circular shape, a rotor section of substantially semi-circular shape, a terminal rod secured solely to one region of said rotor adapted to rotate said rotor, a second terminal rod secured solely to one region of said stator, said rods being parallel and arranged mechanically close for minimizing the inductive reaction thereof, said rotor section having a cut-away portion to permit the close positioning of said rods and full effective one-hundred and eighty degree rotation of said rotor, said stator having a cut-away portion opposite the position of said rotor, and said second rod being asymmetrically placed on the stator, whereby the flow of high frequency current in the condenser through said rods, rotor and stator substantially cancel inductive reaction therein to provide a stable effective capacitance for the condenser when operated at high frequencies.

ADRIANO CAVALIERI DUCATI.
